US0D1089683S

(12) **United States Design Patent** (10) **Patent No.:** **US D1,089,683 S**
(45) **Date of Patent:** **** Aug. 19, 2025**

(54) **MASSAGE DEVICE**

(71) Applicant: **FKA Distributing Co., LLC**,
Commerce Township, MI (US)

(72) Inventor: **Karen Brown**, Kent (GB)

(73) Assignee: **FKA Distributing Co., LLC**,
Commerce Township, MI (US)

(**) Term: **15 Years**

(21) Appl. No.: **29/852,958**

(22) Filed: **Sep. 12, 2022**

(51) LOC (15) Cl. **24-01**

(52) U.S. Cl.

USPC **D24/215**

(58) **Field of Classification Search**

CLAIM

The ornamental design for a massage device as shown and described.

DESCRIPTION

FIG. 1 is a perspective view of a massage device shown in a first configuration according to an embodiment; FIG. 2 is a right side view of the massage device of FIG. 1; FIG. 3 is a left side view of the massage device of FIG. 1; FIG. 4 is a bottom view of the massage device of FIG. 1; FIG. 5 is a top view of the massage device of FIG. 1; FIG. 6 is a front view of the massage device of FIG. 1; FIG. 7 is a rear view of the massage device of FIG. 1; FIG. 8 is a perspective view of a massage device shown in a second configuration according to an embodiment; FIG. 9 is a right side view of the massage device of FIG. 8; FIG. 10 is a left side view of the massage device of FIG. 8; FIG. 11 is a bottom view of the massage device of FIG. 8; FIG. 12 is a top view of the massage device of FIG. 8; FIG. 13 is a front view of the massage device of FIG. 8; and, FIG. 14 is a rear view of the massage device of FIG. 8. The broken lines in the drawings illustrate portions of the massage device which form no part of the claimed design.
